UNITED STATES PATENT OFFICE.

LOUIS ALEXANDRE CADORET, OF PAWTUCKET, RHODE ISLAND.

THREAD-TENSIONING MEANS FOR SHUTTLES.

Application filed August 11, 1927. Serial No. 212,254.

The invention relates to improvements in thread tensioning devices for loom shuttles, and it is intended primarily for use with shuttles which are automatically changed and threaded. The present disclosure of the invention is designed for use in connection with automatic shuttle threaders such as those shown in my U. S. Patents Nos. 1,542,214 of June 16, 1925, and 1,569,712 of January 12, 10 1926.

One object of the invention is to provide an exceptionally simple and inexpensive, yet an efficient and reliable self-adjusting tensioning device disposed at the eye of the 15 shuttle and of such nature as to maintain the proper tension upon the filling or thread, so as to prevent such difficulties as "doubles", "shiners", and "broken picks".

Another object is to provide a construction which is well adapted for use with the 20 automatic threaders shown by the patents above referred to, particularly the threader of the later Patent 1,569,712.

With the foregoing in view, the invention 25 resides in the novel subject matter herein-after described and claimed, the description being supplemented by the accompanying drawings.

Fig. 1 is a fragmentary top plan view of 30 a shuttle equipped with the invention.

Fig. 2 is a longitudinal sectional view through the shuttle showing the thread guiding and tensioning means in side elevation.

Fig. 3 is a top plan view of the threader 35 and the tension device shown in Figs. 1 and 2.

Fig. 4 is an enlarged side elevation of the parts shown in Fig. 3.

Fig. 5 is a longitudinal section on line 5—5 40 of Fig. 3.

Figs. 6 and 7 are transverse sectional views 45 on the correspondingly numbered lines of Fig. 5.

Figs. 8 and 9 are perspective views showing 50 the thread guiding member and the tensioning member separated from each other.

Fig. 10 is a perspective view of the threader 55 and the tensioning device, showing a slightly different form of the latter.

In the drawings above briefly described, 60 preferred features of construction have been shown and while such features will be herein specifically explained, it is to be understood that within the scope of the invention as claimed, numerous variations may be made.

55 The numeral 1 denotes a common form of

shuttle having the usual longitudinal opening 2 for the thread-carrying bobbin 3. The shuttle is recessed at 4 at one end of the opening 2 and a thread-guiding groove 5 is formed in the upper side of said shuttle 60 from the recess 4 to the adjacent shuttle end, this groove coming into play only while the shuttle is being threaded. 5^a denotes the usual slit or the like leading to the eye of the shuttle (not shown).

Secured in the lower portion of the recess 4 is an elongated base plate 6 which is preferably of the general construction disclosed in Patent 1,569,712 above mentioned. This base is provided with an upstanding ear 7 at the 70 inner end of one of its longitudinal edges, said ear having an opening 8 through which a transverse pin 9 passes to anchor the base in the recess 4, said pin overlying the base and passing through suitable openings in the 75 shuttle 1.

Over the base 6, is a thread-guiding member M which is formed of a single piece of wire. One end of this wire is secured to the base 6 and extends in a substantially vertical direction therefrom to provide a thread-guiding leg 10, the wire at the upper end of this leg being coiled at 11 to provide a scroll-like eye which is disposed in a vertical plane transverse to the base 6. From the eye 80 11, the wire is extended to provide an arm 12 which is substantially horizontal and is preferably disposed at about right angles to the plane of said eye. At the end of this arm 85 remote from the eye 11, the wire is bent substantially upon itself as indicated at 13, the wire preferably extending horizontally over a portion of the arm 12 as indicated at 14, and then declining to provide a second relatively short arm 15. In addition to declining from the arm 12, the arm 15 diverges laterally from a vertical plane in which said arm 12 lies, the lower extremity of said arm 15 being secured to the base 6, providing a second thread-guiding leg 16 which is spaced from the leg 10 and 90 is disposed at the inner end of the shuttle eye. 95

The thread-guiding member M is substantially the same as that shown in the two patents above mentioned, and while the legs 10—16 could of course be anchored to the base 6 in any desired manner, the method of anchorage shown in Patent 1,569,712 is preferably employed.

A thread-tensioning arm 17 is disposed 105 longitudinally over the plate 6 either at the 110

inner side of the leg 16 (Figs. 1 to 9) or at the outer side of said leg (Fig. 10). The inner end of this arm 17 is loosely pivoted to the ear 7 by a transverse horizontal pivot 18, permitting vertical swinging of said arm under the influence of the thread or filling T which filling engages the inner sides of the legs 10 and 16 and passes under said arm as it extends to the shuttle eye. The outer end of arm 17 is extended upwardly at 19 and is provided with a vertically elongated guide loop 20 which loosely embraces the arm 12 of the member M, holding said arm 17 against excessive lateral play, regardless of the looseness of the pivot of said arm, necessary to allow free vertical play of this arm.

In the preferred construction, the arm 17 is formed of a single length of wire bent to provide the formations 19-20 at one end and at its other end bent to form an eye 21 through which the pivot 18 passes, said pivot being usually in the form of a rivet.

By preference, a cover C is used with the parts above described, said cover being of the form shown in Patent 1,569,712, above referred to. This cover embodies a top plate 22 which overlies the thread-guiding and tensioning parts and serves to limit the upward swinging of arm 17.

30 The thread T reaches the position shown in Figs. 3, 4 and 10, in the same manner as in the two patents to which I have previously referred. In such position, the thread is frictionally engaged with the loosely pivoted arm 17 and the base 6, thus providing for effective tensioning and overcoming a great many difficulties well known to those skilled in the art, such as "doubles", "broken picks" and "shiners". As the arm 17 is loosely 35 mounted, it can freely move upwardly under the influence of the thread T, but by means of gravity it is self-lowered as conditions require. Thus, it constitutes an effective self-adjusting tensioning device which is mounted at the eye of the shuttle and hence is unusually efficient.

In the form of the device shown in Fig. 10, the structure and arrangement of the parts is exactly the same as shown in the other views 50 except that the thread tensioning arm 17 is disposed at the outer side of the leg 16 instead of at the inner side and this arm 17 acts on the thread in this form of the device in the same manner as in the form shown in 55 the other views.

While the construction herein disclosed may be considered as preferred, attention is again invited to the fact that within the scope of the invention as claimed, numerous variations may be made.

I claim:—

1. In combination with a shuttle thresher having a base and a substantially horizontal portion above said base; a thread-tensioning

arm disposed over the base, means pivotally 65 mounting said arm for vertical swinging, and means carried by said arm and loosely engaged with said portion of said thresher for guiding the vertical movement of the arm.

2. In combination with a shuttle thresher 70 having a base and a substantially horizontal portion spaced above said base; a thread-tensioning arm disposed over the base, means pivotally mounting one end of said arm on the base to permit vertical swinging of said arm, 75 the other end of said arm being extended upwardly, and a vertically elongated guide carried by said upwardly extended arm end, said guide loosely engaging the aforesaid substantially horizontal portion of the thresher. 80

3. In combination with a shuttle thresher having a base, a substantially vertical thread-guiding portion rising from said base and a substantially horizontal portion spaced above said base; a thread-tensioning arm disposed over the base at one side of said vertical portion of the thresher, means at one end of said arm pivotally connecting it with the base, and means at the other end of said arm loosely engaged with said substantially horizontal portion 85 of the thresher for guiding the vertical movement of the arm.

4. In combination with a shuttle thresher having a base, a substantially vertical thread-guiding portion rising from said base and a substantially horizontal portion spaced above said base; a thread-tensioning arm disposed over said base at one side of said vertical portion of the thresher, means pivoting one end 95 of said arm to the base and permitting vertical swinging of said arm, the other end of said arm being upwardly extended, and a vertically elongated guide on said upwardly extended arm end, said guide being loosely engaged with said horizontal portion of the thresher. 100

5. In combination with a shuttle thresher having a base, and an ear rising from said base; a thread-tensioning device loosely mounted on said ear.

6. In combination with a shuttle thresher having a base, and an ear rising from said base; a thread-raised self-lowering thread-tensioning arm loosely pivoted upon said ear. 110

7. In combination with a shuttle thresher having a base, an ear projecting upwardly from said base, a substantially vertical thread-guiding portion rising from the base in spaced relation with the ear, and a substantially horizontal portion spaced above said base; a thread-tensioning arm disposed over the base at one side of said vertical portion of the thresher, means loosely pivoting one end 115 of said arm to said ear, the other end of said arm being extended upwardly, and a vertically elongated guide carried by said upwardly extended arm end, said guide being loosely engaged with said horizontal portion of the thresher. 120

8. A thread-tensioning device comprising an arm provided at one end with means whereby it may be pivotally supported, the other end of said arm being provided with vertical 10 guide means.

9. A thread-tensioning device comprising an arm having means at one end by means of

which it may be pivotally mounted, the other end of said arm being bent upwardly and then downwardly to provide guide means for said 10 arm.

In testimony whereof I have hereunto affixed my signature.

LOUIS ALEXANDRE CADORET.
